CUTTING BOARD

Elizabeth Mason Cairns, Deep Brook Road,
Wyckoff, N.J. 07481

Filed July 23, 1969, Ser. No. 18,348

Term of patent 14 years

Int. Cl. D7—99

U.S. Cl. D44—1

FIG. 1.

FIG. 2.

FIG. 3.

FIG. 1 is a front elevational view of a cutting board showing my new design;

FIG. 2 is a left side elevational view; and

FIG. 3 is a right side elevational view thereof.

The rear of the cutting board is plain and bears no ornamentation.

I claim:

The ornamental design for a cutting board, as shown and described.
